UNITED STATES PATENT OFFICE.

BARTON S. MOLYNEUX, OF MINNEAPOLIS, MINNESOTA, ASSIGNOR, BY DIRECT AND MESNE ASSIGNMENTS, TO THE NATIONAL WATER SUPPLY COMPANY, OF MINNESOTA.

AUTOMATIC FLUID-RELEASER.

SPECIFICATION forming part of Letters Patent No. 400,107, dated March 26, 1889.

Application filed November 24, 1888. Serial No. 291,759. (No model.)

To all whom it may concern:

Be it known that I, BARTON S. MOLYNEUX, of Minneapolis, in the county of Hennepin and State of Minnesota, have invented certain new and useful Improvements in Automatic Fluid-Releaseers, of which the following is a specification.

My invention relates to improvements in a device by which a certain quantity of fluid is released from the reservoir by the introduction of a coin.

My invention consists, generally, in the construction and arrangement hereinafter described, and particularly pointed out in the claims.

In the drawings which form a part of this specification, Figure 1 is a vertical longitudinal section showing the construction of the valve. Fig. 2 is a vertical cross-section on the line *x* *x* of Fig. 1, showing the manner in which the valve is released. Figs. 3, 4, and 5 are details. Fig. 6 is a longitudinal vertical section showing a modification of my device. Fig. 7 is a partial vertical cross-section on the line *y* *y* of Fig. 1.

In the drawings, 2 represents a cask or reservoir to which my device is applied. The receiving-chamber 3 is located, preferably, in the lower part of the reservoir, and is provided with an opening, 5, which receives a suitable branch of the pipe or tube 7, and also the vent-pipe 6, for the passage of air into and out of the chamber 3 as it is emptied and filled with the liquid from the reservoir.

The pipe 7 is provided with a valve, 9, which controls the flow of fluid from the cask to the receiving-chamber 3, and also the flow of liquid from the receiving-chamber through the pipe 7. This valve may be constructed to operate by a partial revolution, as shown in Fig. 1, or it may be arranged to travel back and forth over the opening to the chamber 3, as shown in Fig. 6.

The valve 9 is provided with a stem, 11, which extends outward, preferably, through the pipe 7, and is provided with a suitable handle, 13, by which the valve is operated.

15 represents a case or box, through which the pipe 7 passes after leaving the cask 2. 50 This case or box is preferably made of cast

metal, and the lower portion is detachable in order that access may be obtained to its interior. A conduit, 17, is preferably arranged in the upper portion of the case 15, into which a coin may be placed, and by which the said coin is carried through the case and deposited in the lower portion. A lever, 19, is supported upon the inside of the case 15 upon a suitable pivot, 21. This lever extends forward from its pivoted point, and is provided with a pin or projection, 23, extending across the opening at the mouth of the conduit 17. The opposite end of the lever is preferably provided with a weight, 25, by which the lever may be so balanced that the weight of the coin 22, by which the machine is to be operated, as it strikes the pin 23, will overcome the counter-balance 25, and the lever 19 will be depressed. The upper side of the lever 19 is preferably provided with a notch, 27. This notch is arranged to engage a projection, 29, upon the handle 13. When the lever 19 is depressed, the notch 27 is forced out of contact with the handle 13, which is then free to be operated by the hand. A suitable spring, 31, is preferably secured to the handle 13 in order to bring it back to its normal position after having been operated.

A cut-off, 33, is preferably located in the conduit 17. This cut-off is pivoted or revolved in the said conduit, and is preferably provided with a plate, 35, extending over the inlet to the said conduit. The cut-off 33 and the plate 35 are so arranged that when the plate is forced aside and the mouth of the conduit is open the aperture in the conduit will be closed by the cut-off, and that when the plate 35 covers the mouth of the conduit the cut-off will be turned aside and the conduit left unobstructed for the coin to pass. The object of this is to prevent tampering with the machine.

The plate 35 may be provided with a suitable spring in order to force it over the opening in the conduit, thus keeping it closed in order to avoid the accumulation of dust within the machine.

The operation of the device is as follows: The plate 35 is forced to one side and the coin is introduced into the conduit 17. The

coin will strike the cut-off 33 and there remain until the plate 35 is closed over the mouth of the conduit. When this is done, communication is established through the 5 conduit by the partial turning of the cut-off 33. The coin passes on until it strikes the pin 23 on the lever 19. The weight of the coin depresses this lever. The notch 27 is thrown out of contact with the projection 29 o of the handle 13. Then handle 13 is now free to be partially turned, by which motion the valve is operated, closing the inlet from the cask to the receiving-chamber 3 and establishing an outlet from the chamber 3 5 through the pipe 7 to a cup or receptacle held below the outlet of the said pipe. The handle 13 is held in its forward position until the receptacle is filled or until the contents of the chamber 3 has been emptied. It is then released, and by the action of the spring 31 it is forced back to its original position, and thus closes the outlet from the chamber 3 and establishes a communication between the cask and the chamber 3, by which means 5 the said chamber is again filled. A stop, 20, is preferably secured to the projection 29 of the handle 13, and extends over the opening in the conduit 17, to prevent the coin from passing out of the conduit before o the handle has reached the limit of its throw. When this limit is reached, the coin passes downward between the projection 23 and the stop 20, and falls into the lower portion of the case 15.

5 I prefer to place an intermediate notch, 28, upon the lever 19 to insure the working of the machine, as without this notch, after the lever had been released from the handle and the receiving-chamber emptied, the lever 13 o could be returned a sufficient distance without passing over the notch 27 to allow the chamber to be filled. The handle could then be forced back and the liquid again drawn from the chamber 3. With the interposed 5 notch 28 this is prevented, as the chamber 3 will not be filled until the handle and the operating-valve 9 are in such position as to bring the projection 29 forward to the notch 28, and no liquid can be drawn from the chamber until the projection 29 has passed to the rear or back of the notch 28. It will be seen that the valve is thus securely locked and the handle must be released before another supply of liquid can be drawn. As long as the 5 handle 13 remains in contact with the notch 28 the receiving-chamber 3 is in communication with the reservoir.

In Fig. 6 I have shown a modification in which the valve is arranged to operate by o moving longitudinally of the pipe 7, instead of being partially revolved therein. This necessitates a slight change in the position and operation of the handle 13 and the working parts of the device. The parts are substantially similar in their action, however, and the result obtained is the same. In this modification the handle 13 is preferably pivoted

upon suitable projections of the case 15, and is provided with an extending arm, 41, projecting below the said pivot and engaging the 70 stem 11 of the valve 9. The inner end of the handle 13 projects in front of the opening in the conduit 17 and forms a stop against which the coin strikes. The notches 27 and 28 are placed on the under side of this portion of 75 the handle and are engaged by the end of the lever 19, as shown in Fig. 5. The lever is thrown out of contact with the said notches by the coin as it strikes the pin or projection 23, when the handle 13 will be free to be 80 forced downward, forcing the valve 9 past the opening, communicating with the chamber 3, as shown in dotted lines in Fig. 6. Communication is thus established between the chamber 3 and the outlet of the pipe 7, and is also 85 closed between the cask and the said chamber. At the same time the inner end of the arm is carried upward a sufficient distance to allow the coin to pass from the conduit and fall into the receptacle in the lower portion 90 of the case 15. The lever 19 is now carried back a sufficient distance by the weight 25, and the spring 31, when the handle is released, forces it back to its original position and operates the valve, as before described. 95

I claim as my invention—

1. In a device of the class described, the combination, with a reservoir and a receiving-chamber, 3, located in the reservoir, having a suitable air-vent, 6, and suitable port, 5, of the 100 valve 9, adapted when operated to alternately connect said port 5 with the reservoir and with the pipe 7, a suitable handle, 13, connected to said valve and adapted to operate the same, a suitable weighted lever, 19, adapted 105 to engage said handle 13 and to lock the same, so as to prevent the operation of said valve, and also adapted to be thrown out of engagement with said handle 13 by the weight of a coin, so as to permit the handle to be moved 110 and the valve to be operated, substantially as described.

2. The combination, with a reservoir and a receiving-chamber, 3, of the valve 9, adapted to alternately connect said chamber with the 115 reservoir and with the outlet-pipe, and having a suitable handle, 13, by which it may be operated, and the weighted lever 19, adapted to lock said handle 13, and adapted to be depressed by the weight of a suitable coin and 120 thrown out of engagement with said handle, substantially as described.

3. In a device of the class described, the combination, with a suitable handle, 13, fitted with the spring 31, and adapted by suitable 125 connections to operate the valve of the device, of the weighted lever 19, adapted when in its normal position to engage with and lock said handle 13, and adapted to be depressed by the weight of a suitable coin and thrown 130 out of engagement with said handle, substantially as described.

4. In a device of the class described, the combination, with the valve-actuating lever

13 and the weighted lever 19, engaging the same, of the conduit 17, having the cut-off 33, and adapted to convey a suitable coin onto said lever, so as to depress the same and to 5 throw it out of engagement with said lever 13, substantially as described.

5. The combination, in a liquid-releasing device, of a suitable reservoir, a receiver adapted to receive liquid from said reservoir, 10 a valve controlling the passage of liquid from

said reservoir to said receiver, a coin-conduit, and a latch adapted to lock said valve and to be released by a coin passed through said conduit, substantially as described.

In testimony whereof I have hereunto set 15 my hand this 15th day of November, 1888.

BARTON S. MOLYNEUX.
